UNITED STATES PATENT OFFICE.

JONAS NORTHROP, OF HOPEDALE, MASSACHUSETTS, ASSIGNOR TO HOPEDALE MANUFACTURING COMPANY, OF MILFORD, MASSACHUSETTS, A CORPORATION OF MASSACHUSETTS.

WARP STOP MOTION FOR LOOMS.

Application filed July 2, 1923. Serial No. 349,113.

To all whom it may concern:

Be it known that I, JONAS NORTHROP, a citizen of the United States, residing at Hopedale, in the county of Worcester and

5 State of Massachusetts, have invented certain new and useful Improvements in Warp Stop Motions for Looms; and I do hereby declare the following to be a full, clear, and exact description of the invention, such as 10 will enable others skilled in the art to which it appertains to make and use the same.

The present invention relates to an improvement in warp stop motions for looms.

15 The object of the invention is to reorganize and improve the construction of warp stop motions, and to this end the invention consists in the improvement in warp stop motions hereinafter described and particularly defined in the claims.

20 In the drawings illustrating the preferred form of the invention, Fig. 1 is an end elevation of a loom provided with the present warp stop motion; Fig. 2 is a sectional elevation in a plane parallel to the 25 plane of Fig. 1 looking from the other side; Fig. 3 is a similar view of the parts in a different position; Fig. 4 is a section on the line 4—4, Fig. 2; and Fig. 5 is a plan of the parts with the ratchet shown in section.

The loom frame 1 is provided with a breast beam 2, shipper lever 3 and lay 4, which are or may be all as usual in this class of looms. The warp detectors 5 are 35 mounted on the detector bars 6, and each is provided with a threaded warp which is extended from the frame of the loom forward to the lay. When a warp breaks the warp detector drops and the feeler 7 strikes the operating detector and acts to stop the loom. The feeler 7 is mounted on the 40 feeler shaft 8 which carries on its upper end the lever 9 connected by means of the link 10 with the feeler actuating plate 11 pivoted at 12 on the plate bracket 13. The link 10 extends through a hole in a boss mounted on the side of the shoe 14 which normally rests in a depression 15 in the feeler plate 11. The shoe 14 carries a cam

roll 16 which normally supports the bunter 50 carrier lever 17. The link 10 is adjustably attached to the shoe 14 by nuts screwed up against the opposite sides of the boss which thereby hold the shoe rigidly on the link 10 in a certain position. As the feeler plate 55 11 oscillates the bunter carrier lever normally tends to hold the shoe resting in the depression 15 in the plate and so the shoe and with it the link 10 are reciprocated by the oscillations of the detector plate. As 60 long as the shoe rides in the depression 15 of the detector plate no vertical motion is imparted to the bunter carrier lever, but the feeler continues to be actuated through this means. The detector plate 11 is provided 65 with an arm 18 which is pivotally connected to the link 19 which extends to a bracket 20 secured to the weft hammer 21 actuated by the weft hammer cam 22 in the usual manner. Thus the weft hammer oscillates the detector plate 11.

If now one of the detectors or drop wires 5 falls from the position shown in Fig. 2 to the position shown in Fig. 3, then the feeler 7 is arrested by engagement with the fallen wire. For example, suppose a wire falls with the detector plate occupying the position shown in Fig. 2, and then as the detector 7 moves forwardly, strikes the fallen wire and is thereby arrested and held 70 from further movement, the detector plate 11, however, continues its movement underneath the shoe which is standing still, and lifts the shoe up, thereby lifting the bunter carrying lever 17 which, at its end, carries 75 the bunter bar 23. The bunter bar 23 extends downwardly from the bunter carrier lever 17 and is received between the arms 24 of the guide 25, and below such guide is provided with a bunter 26. With the parts 80 in the position shown in Fig. 2 the bunter is located below the dagger 27 carried by the lay, and the dagger passes over the bunter. When the bunter is lifted up as shown in Fig. 3, the dagger 27 strikes it and 85 moves it rearwardly. To the lower end of the bunter lever 23 is pivotally attached at 90 28 the link 29 which extends rearwardly and

is connected at its forward end to a knock-off lever 30 by which the shipper lever is knocked off.

The mode of operation is apparent from the foregoing description of the parts and relative movements. It will be observed that the bunter carrier lever is provided on its under surface with a curved face which is formed on the arc of a circle of which the 10 pivot 12 is the center, so that as the detector actuating plate 11 is reciprocated, carrying with it the shoe 14, the bunter carrier lever 17 is not oscillated upon its pivot on the bracket 13. But when the shoe is 15 rested by engagement of the feeler with a drop wire, the cam surfaces on the detector plate lift the shoe and thereby lift the bunter carrier and the bunter so as to present the latter to the dagger on the lay. 20 It will be seen that when the feeler is arrested by a fallen drop wire and the shoe 14 thereby raised out of the depression 15 the continued motion of the oscillating parts will cause no further pressure to be exerted 25 by the feeler on the drop wire, except such slight pressure as may be caused by the dragging friction of the feeler plate upon the shoe. Prior warp stop motions ordinarily employ actuating devices which 30 cause a spring pressure to force the feeler against the drop wire, thereby tending to bend or otherwise injure the latter when the feeler has been arrested. According to the 35 present invention any injury to the drop wire due to the engagement with the feeler is substantially eliminated, even where drop wires of very light weight are used.

Having thus described the invention, what is claimed is:—

- 40 1. A warp stop motion for looms having, in combination, warp detectors, a feeler, actuating means for the feeler comprising a detector plate having a depression, cam surfaces on each side thereof, a shoe connected with the feeler, a lever having a portion engaging the shoe normally acting to hold it in the depression in the detector plate but permitting the arrest of the feeler and the lifting of the shoe by the cam surfaces on the 45 detector plate, said lever having a portion received on the shoe, a bunter carried by the lever, a dagger carried by a reciprocating part of the loom, the bunter carrier acting to lift the bunter into the path of the dagger when the feeler is arrested, connections between the bunter and the shipper lever for knocking off the shipper lever when the dagger strikes the bunter.
- 50 2. A warp stop motion for looms having, in combination, warp detectors, a feeler, actuating means for the feeler comprising a pivotally mounted detector plate having a surface provided with a depression, symmetrical cam surfaces on each side thereof, a shoe connected with the feeler having a por-

tion adapted to normally rest in the depression of the detector plate, a bunter-carrier lever pivotally mounted on a stationary part of the loom, having a surface engaging the shoe of such a curvature that when the shoe rests in the depression in the detector plate, such surface is the arc of a circle of which the pivot of the detector plate is the center so that oscillations of the detector plate and shoe under the bunter-carrier lever are inoperative to move that lever which acts to hold the shoe in the depression, a bunter carried by the bunter-carrier lever, a dagger carried by a reciprocating part of the loom, the bunter-carrier lever acting to lift the bunter into the path of the dagger when the feeler is arrested, actuating means for the detector plate, and connections between the bunter and the shipper lever of the loom for knocking off the latter when the dagger strikes the bunter.

3. A warp stop motion for looms having, in combination, warp detectors, a feeler, a detector plate pivotally mounted on a stationary part of the loom having a depression in a portion thereof, cam surfaces symmetrically disposed on each side of said depression, means for oscillating the detector plate continuously during the operation of the loom, a shoe normally resting in the depression of the detector plate, connections between the shoe and the feeler, pressure applying means acting to press the shoe into the depression of the detector plate, a bunter, connections between such pressure applying means and the bunter, a dagger on a moving part of the loom, a shipper lever for the loom, such pressure applying means yielding when the feeler strikes a detector whereupon the shoe is arrested and the feeler plate, continuing its movement, acts by one of its cam surfaces to lift the pressure applying means and thereby to move the bunter into the path of motion of the dagger, and connections between the bunter and the shipper lever to knock off the loom.

4. A warp stop motion for looms having, in combination, a feeler, drop wires normally supported by the warps out of the path of motion of the feeler, actuating means for the feeler comprising a detector plate, means for moving the detector plate continuously during the operation of the loom, a shoe, connections between the shoe and the feeler, said detector plate being provided with a surface upon which the shoe is adapted to rest, a depression in such surface of the detector plate, in which depression the shoe normally remains but out of which the shoe may be lifted when the feeler is arrested, symmetrically disposed cams on the detector plate having portions to engage the shoe and lift it out of the depression when the shoe is arrested by the stopping of the feeler, a device for applying light pressure to the

shoe normally acting to hold the shoe in the depression in the detector plate and having a surface engaging the shoe which is parallel to the motion of the detector plate so that when the latter reciprocates with the shoe in its depression said pressure applying means is not moved, the cam surfaces on

10 said detector plate acting when said shoe is arrested to move the shoe and thereby to move said pressure applying means, a shipper lever for the loom, and connections between said lever and the pressure applying means.

JONAS NORTHROP.
